GERMAIN ROUSSEL, OF FLOREFFE, PENNSYLVANIA.

SAFETY APPLIANCE FOR ELEVATORS.

1,023,277.

Specification of Letters Patent. Patented Apr. 16, 1912.

Application filed May 16, 1911. Serial No. 627,392.

To all whom it may concern:

Be it known that I, GERMAIN ROUSSEL, citizen of the Republic of France, residing at Floreffe, in the county of Allegheny and 5 State of Pennsylvania, have invented certain new and useful Improvements in Safety Appliances for Elevators, of which the following is a specification.

The present invention relates to an improved safety appliance for elevators.

The object of the invention is the provision of means for stopping the descent and preventing falling of an elevator car in the event of breaking of the suspending and 15 operating ropes, thus avoiding injury to the occupants of a passenger elevator car, or damage to the contents of a freight elevator, and the consequent loss by damaged mechanism and machinery attendant upon such 20 an accident.

The invention consists in equipping an elevator with guide beams, which under normal conditions will perform the functions for which they are intended, and which 25 under abnormal conditions as above referred to, will act to jam and wedge the elevator into an immovable position. And the invention further consists in certain novel features of construction for holding the guide beams in normal position against displacement, until called upon to perform their 30 accident-preventing functions.

In the accompanying drawings I have 35 illustrated one example of the physical embodiment of my invention constructed according to the best mode I have so far devised for the practical application of the principles.

Figure 1 illustrates an elevator and its 40 operating mechanism equipped with my novel safety appliance. Fig. 2 is an enlarged detail view of the construction at the top of one of the elevator guide beams. Fig. 3 is a sectional view of Fig. 1, taken at right angles to said view. Fig. 4 is a detail view 45 of a device for preventing outward displacement of the guide beams. Fig. 5 is a horizontal sectional view of Fig. 4 looking downwardly. Fig. 6 is an enlarged detail view of 50 the lower end of one of the guide beams and connections.

In the preferred form of embodiment of 55 my invention the car 1 is suspended by means of two ropes 2 and 3, both ropes being attached to the cage at 4. The rope 2 is the

operating rope, and is passed over the pulley 5 on beam 6, the immovably supported pulley 7, and drive pulley or drum 8, the latter being supported upon the power shaft 9. From the pulley or drum 8 said rope passes 60 around the pulley 10, and is attached at 11 to the underside or bottom of the car 1. The rope 3 is the counterbalancing rope. This rope is passed over the pulley 12 which is supported on the cross beam 13, thence 65 over the pulley 14, and the counterweights 15 at the end of the rope are guided in the channel 16. It is thus apparent that the car may be raised and lowered as usual, by power applied to the shaft 9, and the action 70 of the counterweights is the same as in standard devices of this character.

The beam 13 at the upper end of the elevator shaft or well is stationary and permanently located. The beam 6 which is located 75 directly above the beam 13 is suspended and held at its lowest position by means of the pair of yokes 17 which are U-shape and supported on the immovable beam 18. A pair of coiled springs 19, of sufficient strength for 80 the purpose, is interposed between the cage supporting beam 6 and the permanent beam 13, and these springs are held under tension by the weight of the car, the latter being supported by the rope 2 which passes over the pulley 5 on the beam 6. From this construction 85 it will be understood that the beam 6 is suspended and held by means of the yokes 17, and that the weight of the car holds the springs in compressed position.

The springs 19 are the actuating elements 90 for the safety appliance. The safety appliance comprises a pair of guide beams 20 and 21 located centrally of the elevator and at either side thereof, and which project 95 into guide slots in the upper and lower guide bars 22 and 23 of the elevator cage. In Fig. 1 the guide beams 20 and 21 are illustrated in their normal positions and the 100 car is free to move in ascending and descending, being guided by the beams as usual. The beams are supported on the stationary cross bar 24, which is located at the bottom of the elevator well or pit, by a wheel or roller 25 journaled in the lower 105 end of each beam, and a second pair of rollers 26, located at the upper ends of the beams, bear against the stationary beam 13. Each of the beams or bars 24 and 13 are 110 slotted or grooved (see Fig. 3) at 27 for

confining the rollers and guiding their movement. As will be apparent, these beams 20 and 21 are movable, and to prevent their displacement in an outward direction, I 5 provide a series of locking latches 28, each pivoted at 29 to either of the beams 20 or 21, and having their free ends resting in slots or depressions 30 in the upright standards 16 and 31. It will be noted that the two 10 uppermost latches 32 are pivoted at 33 to the respective standards 16 and 31.

To prevent the unintentional inward movement and displacement of the guide beams 20 and 21, I provide a pair of locking levers 34 and 35 at the lower end of the beams 20 and 21. These levers are pivoted respectively at 36 and 37 on the bar 38, and their free ends 39 engage in recesses 40 on the guide bars 20 and 21. A second pair of 20 levers 42, are pivoted at 43 to the bar 13 and their free ends are engaged in similar recesses 40. Each of the levers is held in place by a spring 41, which is attached at its ends to a lever and one end of the guide 25 beam 20 or 21. In this manner the guide beams 20 and 21 are braced at either side and held in normal position by the latches 28 and levers 34, 35 and 42.

The safety appliance is actuated by the 30 breaking of rope 2 in manner as follows. A pair of duplicate ropes 44, are attached one at each end of the cross bar 6. These ropes, which may be termed safety ropes, extend down the entire distance of the elevator shaft or well, and at the bottom of the pit pass under the oppositely disposed pulleys 45 to the respective levers 34 and 35, one being attached to each lever. An idle pulley 46 is provided for one of the ropes, 40 said pulley being supported on the bar 24. The ropes 44 for convenience of location and operation, are passed through slots 47 in the series of locking latches 28, and are attached to the levers 34 and 35 at points 45 48, which are formed as attaching eyes. A second pair of safety ropes 49 are attached to and suspended from the bar 6, and each of these ropes passes around a pulley 50 on the bar 13, and is attached at 51 to one of 50 the levers 42.

Now assuming the car to be in position shown in Fig. 1, should rope 2 break, the elevator cage starts to drop. Simultaneously with the breaking of the rope, the bar 55 6, which has been held down by the weight of the elevator, as described, is lifted upwardly by the springs 19 which have been freed as the weight is taken off the bar 6. The upward lift of bar 6 pulls upon the 60 ropes 44 and 49. The ropes 49 pull on the levers 42 and disengage them from the notches 40, and the ropes 44 draw their respective levers 34 and 35 from engagement with the notches 40 in the beams 20 and 21, and the continued pull on the two pairs of

ropes through the elements 41 (which may be connecting links if desired) draws the beams 20 and 21 toward each other. The beams travel on their rollers, in the grooves as described, and clamp the car between them, thus frictionally holding the car in place, and preventing its descent. 70

An additional safety feature is provided by the levers 52 carried on the elevator car. These levers are adapted to engage the cross bars or studs 53 on the guide beams 20, 21, and hold the elevator car, in addition to its frictional engagement with the beams, while the ropes are being mended. The levers 52 have attached to their weighted ends 54, 80 draw rods 55, and by means of the draw rods, to which is attached the rope 2, the levers 52 are held to travel in a path, out of engagement with the studs 53. But when the rope 2 breaks, the draw rods are freed, and the weighted ends 54 of the levers are forced downwardly while the ends 52 are forced out and upwardly in position to engage the next lower stud 53. As a warning signal, in case of accident, the bell 55' may 90 be rung as it is struck by the arms 56 on the draw rods 55. 95

From the above description, taken in connection with the drawings, it is believed the merits and advantages of my invention will be apparent, and it is evident that I have provided a safety appliance for elevators which will perform the functions of a perfect mechanism for the purpose. 100

Having thus fully described my invention, what I claim as new and desire to secure by Letters Patent is:—

1. The combination with an elevator car and its operating mechanism, of a pair of movable guide beams, stationary standards, means connected to said beams and engaging said standards for preventing outward lateral movement of the beams, and means for holding said beams against inward lateral movement. 105

2. The combination with an elevator car and its operating mechanism and an upper and lower stationary bar, of a pair of bodily movable guide beams, rollers at the ends of said beams engaging said bars, means for holding said beams against inward lateral movement, and means actuated by the disarrangement of the operating mechanism for releasing the holding means and drawing said beams into frictional contact with the elevator car. 115

3. The combination with an elevator car, its operating mechanism, a pair of standards, and an upper and lower stationary bar, of a pair of bodily movable guide beams, rollers at the ends of said beams engaging said bars, means on the guide bars engaging said standards to prevent outward lateral movement of the beams, means for locking the beams against inward lat- 125

eral movement, and means actuated by the disarrangement of the operating mechanism for unlocking said means and drawing the beams into frictional engagement with the 5 elevator car.

4. The combination with an elevator car, a stationary support, a movable support held under tension, and a movable guide beam, of a device for locking the beam 10 against inward lateral movement comprising a pivoted locking lever having yielding connection with said beam and positively engaging the beam, and a connection from said lever to the movable support whereby 15 movement of said support disengages said lever from said guide beam.

5. The combination with an elevator car and a movable support therefor held against

tension, of a stationary standard, and a movable guide beam, anti-friction rollers 20 at each end of said beam, cross bars forming tracks for said rollers, and locking latches pivoted on said guide beam engaging the standard, upper and lower pivoted locking levers engaging said beam, and separate connections from each locking lever 25 to the movable support, whereby upward movement of the support pulls said beam inwardly.

In testimony whereof I affix my signature 30 in presence of two witnesses.

GERMAIN ROUSSEL.
